ALBERT E. SEREWICZ, OF CHICAGO, ILLINOIS.

SPARK PLUG AND METHOD OF MAKING SAME.

Application filed October 27, 1919. Serial No. 333,751.

To all whom it may concern:

Be it known that I, ALBERT E. SEREWICZ, a citizen of the United States, residing at Chicago, in the county of Cook and State 5 of Illinois, have invented certain new and useful Improvements in Spark Plugs and Methods of Making Same, of which the following is a specification.

This invention relates to spark plugs such 10 as are used in internal combustion engines, and a method of making them, and among the objects of my invention are to so improve upon the structure as to reduce the possibility of short circuit; to reduce the 15 possibility of breaking the insulation; to produce a new plug and a corresponding new method of manufacture; to improve upon the construction of spark plugs in general; and to secure such further and incidental objects and advantages as will 20 later more fully appear.

In most prior spark plugs, the insulator, passing through the shell by which the plug is mounted in the engine, extends above the 25 top of the shell and is therefore exposed in such a manner that it is easily broken accidentally. Furthermore, it is exposed to cold drafts of air and to accidental splashing of water, as when it is necessary to raise 30 the hood out of doors during a rain, and it is therefore likely to be cracked from one of these causes. Also, with the electrode projecting above the top of the insulator, one 35 is likely to get shocks by accidentally touching the electrode, and this is obviated by having this part terminate within a hollow in the end of the insulator so that it is impossible to touch the electrode when the same is "live," except by using some tool 40 and making a definite purposeful effort to do it. It has been common, though not universal practice, to secure the insulator within the shell by means of a detachable ring or gland engaging screw threads in or on 45 the shell. The cutting of the threads on the shell and ring or gland is expensive, and furthermore, insulators are often cracked by the gland's being screwed in too tightly. I have obviated this by my new method of 50 manufacture.

When the firing point, usually connected to the shell, is put into a hole drilled longitudinally into the end of the shell and then bent over into proximity to the central electrode, an entirely separate operation is 55

involved in the drilling of the hole in the shell, it being necessary to remove the shell from the machine in which the threads are cut and put it into another, in which the hole is drilled. This I have obviated by 60 drilling the hole transversely through the edge of the shell, which can be done while the shell is being held stationary in the machine in which the threads are cut.

In the accompanying drawing, showing 65 my invention, Fig. 1 is a longitudinal section of a completed plug provided with a central electrode adapted to receive any ordinary snap connector.

Fig. 2 is a longitudinal section of a completed shell before the insulator has been applied, and Fig. 3 shows a plug, partly in elevation and partly in longitudinal section, provided with a central electrode having its external end screw-threaded for attachment 75 of a screw-threaded connector.

Referring more in detail to the drawing, in which A represents the shell, B the insulator, C the central electrode, and D the connector adapted to engage the external 80 end of the electrode, 1 represents the wrench flange of the shell A, and 2 the screw-threaded end, common in structures of this character. 3 is a shoulder formed 85 within the shell, against which rests any suitable gasket 4 to cushion the insulator and form a tight joint between the shell and the insulator. 5 is a flange on the insulator B adapted to press against the gasket 4 and to be engaged by an inwardly 90 flexed part 6 of the shell A, the upper and lower faces of this flange being preferably inclined outwardly, although this is not necessary.

The insulator B is made hollow at its 95 outer end, as shown at 7, and within this hollow, preferably near its inner end, is the end 8 of the central electrode C, the shaft of which is molded in to the body of the insulator so that it is held firmly therein, and leaves no opportunity for the escape 100 of gases between the electrode and the insulator. As shown in Fig. 1, this end 8 is provided with a ball which may be engaged by a spring connector. This terminal or 105

outer end 8 may be made in various forms to adapt it for use with any of the several standard forms of connector. It is shown in Fig. 3 that this end, instead of having a ball, may be screw-threaded and there- 110

- fore may have a screw-threaded connector secured thereto, as shown at 10. In the latter case, the conductor 11 passes down through a hollow in an insulating member, 5 and has its inner end spread out so that when the connector D, carrying the sleeve 10, is screwed into place, intimate contact will be caused between the end of the conductor 11 and the end of electrode C.
- 10 It will be observed in Fig. 2 that shell A is provided with a cylindrical opening in its outer end, and that flange 9 is connected with the body of the shell by a comparatively thin wall 6, so that when the 15 insulator B is put into the shell and the latter is compressed longitudinally, the wall 6 will yield inwardly and press tightly against the flange 5 of the insulator, thereby preventing it tightly against the gasket 4, and 20 preventing any leakage of gas between these parts. It will also be observed that in this method of manufacture, a space is left between the upper end of the insulator and the flange 9, forming the top of the plug.
- 25 The groove in the outer wall of the plug is turned in such a manner as to cause the wall to flex inwardly when compressed longitudinally and flex most sharply at the lower part, the same being progressively 30 thickened from the thinnest portion below to the full thickness of the flange above. In this way a sort of metal cushion is formed whereby undue pressure caused by the press on the insulator during the assembling operation, is avoided. The flange 9, 35 being longer than the insulator, allows a machine to be used to compress the shell longitudinally without danger of fracturing the insulator, thereby causing a very 40 tight fit between the insulator and its co-operating parts. This flange 9 also prevents cold air currents from striking the insulator as well as preventing water from splashing thereon from any side. Furthermore, 45 since there is a space between the flange and the end of the insulator, this space will serve as an air jacket for the protection of the insulator.
- 50 During the process of manufacturing the shell, a hole 13 is drilled through the inner end thereof and a pin or firing point may be inserted in this hole to extend a suitable distance inwardly toward the central electrode C. After this pin 14 has 55 been inserted, the metal of the shell is indented sufficiently to cause the pin to be firmly held in place. This method of manufacture is very useful since it permits the drilling of the hole in the shell to be done 60 while the shell is held in the machine by which the thread is formed thereon without the necessity of an extra operation, which 65 operation, it has been found in practice, results in the breaking of numerous drills because the parts are not properly held.

As pointed out above, several advantages are secured by providing the flange 9, which extends outwardly far enough when the spark plug is completed so that the outer end of the insulator is entirely protected 70 from external blows and forces. It is also a considerable advantage to have the outer end of the electrode terminating well within the outer end of the insulator and sleeve so that not only is short circuiting prevented, but no blows can reach this electrode accidentally, thereby cracking the insulator, as is so common in cases where the electrode projects considerably beyond the end of the insulator. 75

It is believed that the construction and operation of my device will be obvious from the foregoing without more detailed explanation, and it is of course understood that the specific description of the structure and 80 methods set forth above may be departed from without departing from the spirit of my invention as set forth in this specification and the appended claims.

Having now described my invention, I 90 claim:

1. A spark plug comprising longitudinally apertured body and flanged portions, an insulator therein and having a flange, said body portion having a shoulder for 95 the flange of the insulator, said body and flange portions being connected by a part which is thinner than the flange, said part being adapted when the body and flange portions are forced toward each other to 100 flex to form a shoulder for the flange of the insulator.

2. A spark plug comprising a shell longitudinally apertured, the aperture at one end being larger than at the opposite end, 105 whereby a shoulder is formed at the junction of the two parts, an insulator having a flange resting against the shoulder and held in place by an inwardly bent portion of the shell pressing against the flange of 110 the insulator to hold the same tightly against the shoulder, said shell having a flange connected to the said inwardly bent portion and extending outwardly beyond the end of the insulator. 115

3. A spark plug having a longitudinally apertured shell provided intermediate its ends with a shoulder, a flanged insulator pressing against said shoulder, the said shell having a flange connected to the body 120 thereof by a relatively thin portion flexed inwardly to press against the flange of the insulator, thereby holding the same in position, said insulator having a hollow outer end terminating within the outer end of the 125 flange and separated therefrom by an air space.

4. A spark plug having a longitudinally apertured shell provided intermediate its ends with a shoulder, a flanged insulator 130

- pressing against said shoulder, the said shell having a flange connected to the body thereof by a relatively thin portion flexed inwardly to press against the flange of the insulator, thereby holding the same in position, said insulator having a hollow outer end terminating within the outer end of the flange on the shell, and separated therefrom by an air space, said insulator being provided with a longitudinally disposed electrode terminating inwardly near the inner extremity of the shell and terminating outwardly within the hollow in the end of the said insulator.
15. The method of making a spark plug comprising forming an apertured shell with a flexible portion intermediate the ends of the shell which portion is thinner than the flange, placing a flanged insulator in said shell with the flange of the insulator seated upon a shoulder formed in the shell, longitudinally compressing the shell to cause an inward flexing of the intermediate rela-
- tively thin portion for forming a second shoulder for the flange of the insulator. 25
6. A spark plug comprising an apertured body portion having an internal shoulder, an insulator located in said body portion and seated on said shoulder, an apertured flanged portion connected to said body portion by a flexible portion which is thinner than the flange, said flexible connecting portion extending inwardly into contact with insulator for forming a second shoulder therefor. 30
7. A spark plug comprising a shell, an insulator mounted in the shell and having its outer end terminating within the outer end of the shell, said shell having a thin wall portion intermediate the ends of the shell and capable when the shell is longitudinally compressed to flex into tight engagement with the insulator. 35

In witness whereof, I hereunto subscribe my name to this specification.

ALBERT E. SEREWICZ.
